UNITED STATES PATENT OFFICE.

MICHAEL HEYMAN, OF CINCINNATI, OHIO.

NECKTIE.

1,270,413.

Specification of Letters Patent. Patented June 25, 1918.

Application filed January 24, 1912. Serial No. 313,459.

To all whom it may concern:
Be it known that I, MICHAEL HEYMAN, a citizen of the United States, and a resident of Cincinnati, in the county of Hamilton and State of Ohio, have invented certain new and useful Improvements in Neckties, of which the following is a full, clear, and exact description, reference being had to the accompanying drawing, forming part 10 of this specification.

The object of my invention is to provide a simple, inexpensive and effective way to secure in position the inner lining of cravats and neckties to prevent the lining becoming 15 rolled up and working loose, as it is very apt to do when inserted loosely in the folds of the tie.

The desirability of securing the lining in place has of course been recognized, but inasmuch as such lining cannot be stitched 20 through the tie after it is folded, as the stitching would show through the front of the tie, and as it is impractical ordinarily to stitch the lining through the back,—ordinarily 25 linings for ties are merely laid in loose within the folds of the material. In order that the lining may be stitched to the back of the tie after it is folded and sewed together, very expensive specially designed sewing 30 machines have been provided, and to accomplish the result it is necessary to make use of such special machine.

It is the object of my invention to obviate the necessity of any special, expensive 35 machine to stitch the lining in place and to utilize the ordinary sewing machine for doing the work. This I accomplish by that 40 novel method of procedure to be hereinafter particularly pointed out and claimed, in which the lining is stitched or secured to the fabric before the tie is folded.

In the drawing,
Figure 1 is a plan view representing the 45 goods for the tie before folding.

Fig. 2 is a plan view of the lining.

Fig. 3 is a similar view with the lining stitched to what will be the rear fold of the tie.

Fig. 4 is a plan view of a tie with the lining 50 stitched in place and folded and the folds secured, with the middle portion wrong side out.

Fig. 5 is a similar view, with the tie portion right side out.

Figs. 6 and 7 are respectively cross sections on the lines 6—6 and 7—7, of the tie, as shown in Figs. 4 and 5.

In each of the views only one end, the broad end, of the four-in-hand tie is illustrated, but it will be understood that the 60 lining extends from one end of the tie to the other, but it is in the larger flaring end that the most disadvantage arises from the loose lining.

The material 1, from which the tie is to be 65 formed, is cut of the ordinary length, in the present instance for a four-in-hand tie, and as I have said, I have only illustrated the broad end. The lining 2 is cut of the proper shape, usually triangular to fit within the 70 folds of the goods when the tie is folded, and this lining is then stitched on an ordinary sewing machine or by hand to the back of the goods, or the reverse side, as I have 75 illustrated in Fig. 3, by the stitches 3, 3. The lining when thus stitched extends slightly beyond the one edge 4 of the goods and any number of lines of stitching may be provided as desired. The outer line of 80 stitching, parallel with the edge of the goods, is located some little distance within the edge. The goods is then folded wrong side out and the edges of the tie material 85 stitched together. This work leaves the lining extending beyond the stitched edge of the tie. The tie is then turned inside out and the folds pressed down so that the lining 90 extends beyond the stitched line 5 of the folds, and thus completely lines the broad portion of the tie from the neck portion to the lower end.

Stitching the lining with a line of stitches considerably inside the edge of the unfolded goods as illustrated in Fig. 3, permits me to bring the stitch line for the folded goods 95 some distance inside the edge and allows the lining to fill out the folded tie from side to side.

My tie when folded, however, provides the stitched line for securing the goods together 100 at one side of the middle line of the tie instead of down the middle portion of the back, as is usually the case for such ties.

One of the reasons why it has not been an obvious matter to secure the lining before 105 the goods are folded over, has been that it is necessary that the lining should extend from one side to the other in the fold of the tie,

and therefore it did not seem practicable to sew the lining in place before folding.

I have overcome the difficulty by securing the lining entirely on one side of the back 5 fold portion and allowing it to lie loose under the other back fold. Inasmuch as the line of stitching falls considerably beyond the middle line, this loose portion is not sufficiently wide to roll up and always remains 10 flat. Another advantage from the secured lining is that it being usual to cut the goods on the bias, the lining prevents stretching.

Having thus described my invention,

what I claim as new and desire to secure by Letters Patent, is:—

A necktie with the material folded lengthwise and stitched together, and provided with a lining extending the width of the folded tie from side to side and permanently secured to one of the back folds and extending across the seam of the back folds, without attachment to the other back fold and lying loosely under the seam joining the folds.

MICHAEL HEYMAN.
